UNITED STATES PATENT OFFICE.

CHARLES L. HOWARD, OF CAPAY, CALIFORNIA.

AUTOMATIC PIN-COUPING.

1,127,894.

Specification of Letters Patent.

Patented Feb. 9, 1915.

Application filed March 11, 1913. Serial No. 753,532.

To all whom it may concern:

Be it known that I, CHARLES L. HOWARD, a citizen of the United States, residing at Capay, in the county of Yolo and State of California, have invented new and useful Improvements in Automatic Pin-Couplings, of which the following is a specification.

This invention relates to automatic pin couplings for vehicles, and while intended primarily for use on traction engines, may be applied and will operate with equal facility upon railway cars and all other vehicles upon which pin couplings are used or desired.

15 The object of the invention is to generally improve devices of this character with a view to simplicity, strength and economy in construction, and ease and certainty in automatic operation.

20 With this object in view, the invention consists in the improved construction, arrangement and combination of the parts of an automatic coupling for vehicles, all as hereinafter fully described and afterward 25 specifically claimed.

In order that its construction and operation may be readily comprehended, I will now proceed to fully describe my invention in connection with the accompanying drawing, which illustrates an approved embodiment thereof and in which—

Figure 1 represents a sectional view taken on the plane indicated by the broken lines 1, 1, of Fig. 3, looking downward as indicated by the arrow, the parts being in position to be automatically operated by being moved against a pin in the other vehicle to be coupled; Fig. 2 represents a similar view with the parts in their coupled position and 40 locked against accidental uncoupling; Fig. 3 represents a view in side elevation with the parts coupled; and Fig. 4 represents in a top plan view, one of the jaws detached.

Like reference characters mark the same 45 parts in all of the figures.

Referring specifically to the drawings 5 indicates a drawbar of any approved material and construction, and which may form a permanent part of the vehicle upon which

the invention may be used, or detachable 50 therefrom and used upon another vehicle, as may be desired.

The coupling illustrated comprises a drawhead formed integral with the drawbar 5 by bifurcating the latter at its outer 55 end thus forming upper and lower plates 6, 6, separated by a space 7 a sufficient distance to receive two coupling jaws 8 and 9 which are pivotally mounted between the plates 6, 6, by pins 10 and 11 located near 60 the outer edges of the jaws and plates. The plates 6, 6 are alike in construction, each being slotted centrally and longitudinally in their outer ends, as at 12, forming thereby two pairs of complementary shoulders 13, 65 the inner faces of the outer ends of which are outwardly beveled to provide guides for directing the coupling member of another vehicle between the coupling jaws 8 and 9, as will hereinafter be more fully described. 70

The drawhead is longitudinally recessed in the outer end of its solid portion, as at 14, said recess opening into the space between the plates 6, 6, and serving to receive a latch 15 normally and yieldingly held in 75 its outer position, projecting into the throat of the space 7 between the jaws 6, 6, by any suitable means, such for instance as a spring 16 bearing at its outer end against a shoulder 17 on the latch 15 and at its inner end 80 upon the bottom of the recess 14. This latch is slotted transversely at 17^a to permit of the passage of an operating bar or handle 18 pivoted in a transverse recess 19 in the drawbar on a pin 20 and projecting through 85 a recess 21 beyond the side of the drawbar, said recess 21 being of sufficient width to permit oscillation of the bar 18 far enough to withdraw the latch bar entirely into its containing recess 14 and out of the space 7. 90

The outer ends of the jaws 8 and 9 are rounded off, as at 22 and extend beyond the central longitudinal axes of the plates 6, 6, each entirely crossing the slots 12 in said plates, but lying within the plane of the 95 outer ends of the shoulders 13 each jaw being notched on its inner edge, as at 23, forming the outer ends into hooks 24 having

inner faces 25 at substantially right angles to the lengths of the jaws, the inner walls 26 of the slots 23 being similarly located with reference to the lengths of the jaws. 5 The outer end of each jaw is beveled off as at 27 and its inner edge cut away at 28 to form a face 29 for purposes hereinafter described.

The operation of the invention may be described as follows: The parts being in the positions illustrated in Fig. 1, with the latch in its normal position extended into the space 7 between the plates 6, 6, and the jaws adjusted so that their inner ends are crossed 15 over toward the edges of the plates 6, 6, opposite to those near which the pivot pins 10, 11 are located, far enough to bring the beveled corners 27 outside of the end of the latch, and the curved outer ends of the plates 20 and hooks slightly overlapping (or it might be entirely separated), the vehicle carrying the coupling is moved toward the one to which it is to be coupled until a coupling pin 30, guided by the beveled fixed faces of 25 the shoulders 13, is pressed upon the hooks 24, and these hooks being free to move on their pivots, the pin 30 presses the hooks apart and passes in between them. The continued movement of the pin 30 between the 30 hooks brings it into contact with the inner faces 26 of the notches 25 in the jaws, and pressure against said faces, presses the beveled inner ends 27 of the jaws against the outer end of the latch 15, moving said latch 35 upward until the inner ends of the jaws pass to the opposite sides of the latch to the positions shown in Fig. 2. Any inward pressure of the pin 30 now, will cause the edges 28 to be in contact with the sides of 40 the latch and prevent the jaws from being moved in a direction to allow the hooks to part and release the pin. When however it is desired to release the pin to uncouple the vehicle, it will only be necessary to move 45 the latch handle bar 18 inward, thus pressing the latch inward against the stress of the spring, until the outer end of the latch no longer projects into the space 7, when the jaws will be free to rock on their pivots, and 50 any outward pressure of the coupling pin 30 against the inner faces 25 of the hooks 24 will rock the jaws and separate the hooks, allowing the coupling pin to pass out between them. Upon release of the latch handle, the latch will be pressed outward into 55 the space 7, in the position shown in Figs. 1 and 2, with jaws in position to again automatically couple two vehicles together.

While I have specifically described the 60 construction, location and operation of the several parts of my improved coupling, it will be obvious to those skilled in the art that slight changes and modifications may be made therein without departing from the 65 spirit and scope of the invention as claimed.

Having thus fully described my invention, what I claim as new and desire to secure by Letters Patent of the United States is.

1. An automatic coupling comprising a 70 drawhead having upper and lower plates with a space between them, superposed jaws in said space having notches in their inner edges with forward and rear walls at right angles to the length of the jaws forming 75 overlapping hooks, a spring latch projecting into the inner end of the space between the jaws, and beveled corners at the inner ends of the jaws, whereby inward pressure on the inner walls of the notches will cause 80 the inner ends of the jaws to pass from one side of the latch to the other, and lock the hooks in coupling position.

2. An automatic coupling comprising a 85 drawhead having upper and lower plates with a space between them, superposed jaws in said space having notches in their inner edges with forward and rear walls at right angles to the length of the jaws forming overlapping hooks, a spring latch projecting 90 into the inner end of the space between the jaws, beveled corners at the inner ends of the jaws whereby inward pressure on the inner walls of the notches will cause the inner ends of the jaws to pass from one side 95 of the latch to the other, the faces of the ends of the jaws opposite to the beveled corners being adapted to engage the latch and prevent their return.

3. An automatic coupling comprising a 100 draw head provided with a longitudinal recess and having upper and lower spaced plates terminating each in a pair of spaced outwardly beveled shoulders, a latch seated in the recess, a spring operating normally 105 to hold the latch projected into the space between the plates, a pair of overlapping jaws in the space each having inwardly projecting overlapping hooks at their outer ends 110 that lie within the plane of the outer ends of the shoulders and notches in their inner faces having transverse walls, and a pair of pins pivoting the jaws at points near the outer edges of the plates, the jaws at their inner ends each having on one side a beveled corner to pass over the latch when moved in one direction, and on the other side a face in line with the length of the jaws to engage the latch and prevent movement in the opposite direction. 115

4. In a car coupling, in combination, a housing, oppositely arranged forwardly extending arms formed upon said housing, alining spaced apart pivots mounted upon said arms, two lever jaws, rightangularly 125 disposed hooks formed upon said lever jaws, said hooks being eccentrically fulcrumed upon said pivots, each of said lever jaws being formed at its inner ends with oppositely beveled edges merging with curvilinear 130

edges, a slidable member projecting between the curvilinear edges of said jaws to hold said jaw hooks in closed relation, said hooks being separated to cause the beveled edges 5 of said jaws to engage the diagonally opposite edges of said slidable member, and means for guiding said slidable member.

Copies of this patent may be obtained for five cents each, by addressing the "Commissioner of Patents, Washington, D. C."

In testimony whereof, I affix my signature in presence of two witnesses.

CHARLES L. HOWARD.
